UNITED STATES PATENT OFFICE.

CHRISTIAN WILLIAM MEINECKE, OF JERSEY CITY, NEW JERSEY, ASSIGNOR
TO MEINECKE & COMPANY, OF NEW YORK, N. Y.

DESIGN FOR A WATER-BAG.

SPECIFICATION forming part of Design No. 34,117, dated February 19, 1901.

Application filed January 26, 1901. Serial No. 44,951. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Water-Bag, of which the following is a specification.

My invention relates to a new and original design for water-bags, and is illustrated in the accompanying drawing, in which the figure is a side elevation.

The leading features of my new design reside in a water-bag provided with projections from its opposite ends intermediate its sides, said projections provided with substantially central perforations, and a circular neck having a mouth jutting out from one end of the water-bag at one side of one of the projections.

In the said drawing the reference-letter A indicates the water-bag, having projecting

from its opposite ends B B and intermediate the sides C C projections D D, formed with substantially central perforations E E. The reference-letter F indicates a circular neck 25 having a mouth jutting out from one end of the water-bag at one side of the projections D.

My design presents a water-bag having a novel, pleasing, and distinguished appearance.

Having thus described my invention, what I claim is—

The design for a water-bag substantially as herein shown and described.

In testimony whereof I have hereunto set 35 my hand in presence of two subscribing witnesses.

CHRISTIAN WILLIAM MEINECKE.
